TYPEWRITER DESK MOUNT

William M. Fritch, Jasper, Ind.

Application April 23, 1939, Serial No. 270,637

2 Claims. (Cl. 312—22)

This invention appertains to new and useful improvements in mounts for typewriters and more particularly to a built-in mount for desks.

A principal object of the present invention is to provide a typewriter mount for desks which in construction will simulate an ordinary drawer of the desk.

Another important object of the invention is to provide a mount for typewriters which will utilize a compartment of a desk for concealment in a drawer-like structure.

Other objects and advantages of the invention will become apparent to the reader of the following specification.

16 In the drawings:

Figure 1 represents a fragmentary perspective view showing the mount in useful position.

Figure 2 represents a perspective view showing the mount in lowered position.

20 Figure 3 is a fragmentary longitudinal sectional view through the mount showing the same in concealed position.

Figure 4 is a section on the line 4—4 of Figure 3.

Figure 5 is a sectional view on the line 5—5 of Figure 4.

Figure 6 is a sectional view on the line 6—6 of Figure 1.

Referring to the drawings wherein like numerals designate like parts, it can be seen that 30 numeral 5 generally refers to a desk of which construction the top is denoted by numeral 6 and the frame by numeral 7. The frame is so constructed as to afford a tier of drawers. Each drawer opening has the slide runners 8 and 9 disposed above and below the drawer.

35 In carrying out the present invention a drawer-like structure generally referred to by numeral 10 is employed. This structure consists of the bottom 11, the front wall 12 and one side wall 40 40 45 13. The front wall 12 is somewhat higher than the side wall 13, but of substantially the same height as the rear wall 14.

45 Into the upper edge of the side wall 13 is driven the eye member 15 and from this eye member 15 is disposed the rod 16 which has its outer end disposed into the front wall 12 and preferably passing through another eye member 17 driven into the upper edge of the wall 13.

50 Numeral 18 represents the swingable platform for the typewriter 19 and this has a pair of depending eye members 20—20 adjacent one edge portion thereof, which are slidably disposed on the rod 16.

55 It can be seen, as shown in Figure 4, that when the platform 8 is slid inwardly to a position avoiding the front wall 12, it can be swung down-

wardly so that the typewriter is disposed entirely into the drawer-like structure 10, and when this has been done the drawer-like structure can be shoved inwardly with the result that the typewriter is not only disposed out of the way but entirely concealed.

When the platform 18 is to be used, the drawer-like structure 10 is moved outwardly, after which the platform 18 is swung upwardly to the position shown in Figure 1, and moved outwardly 10 so that it rests on the upper edge of the wall 12.

The wall 14 has a cleat 22 secured to the upper edge portion thereof, and embedded in the top surfaces of the wall 14 and cleat 22 are the sockets 23 containing the rotatably mounted 15 rollers 24 which ride against the upper guide runners 8. Like anti-frictional means is provided between the bottom of the drawer-like structure 10 and the lower guide runners 9.

It will be observed that in the drawings the typewriter drawer and mount are shown in the right pedestal of the desk. This is desirable when the user writes with his left hand. In the event the user of the typewriter is right handed it will be more desirable to have the drawer and typewriter mount in the left pedestal of the desk.

25 While the foregoing specification sets forth the invention in specific terms, it is to be understood that numerous changes in the shape, size and materials may be resorted to without departing 30 from the spirit and scope of the invention as claimed hereinafter.

Having described the invention, what is claimed as new is:

1. In combination with a desk, a drawer having a front wall and one side wall, a guide rod on the side wall, a typewriter supporting platform, means slidably connecting the platform and the guide rod, said platform being adapted to be swung downwardly into the drawer, or upwardly and slid outwardly to partly rest on the front wall of the drawer.

2. In combination with a desk drawer, a typewriter supporting platform; said drawer having a side wall and a front wall, said front wall rising higher than the upper edge of the side wall, a guide rail disposed in parallel relation to the upper edge of the side wall and being secured thereto, said platform being provided with depending eye members receiving the guide rail and being slidable and rotatable thereon, said platform being swingable into the drawer into a position substantially parallel to said side wall where it is out of use and being swingable upwardly and slidably forwardly to a horizontal position for use in which it rests upon said front wall.

WM. M. FRITCH.
